EDGAR H. BURROUGHS, OF SCARSDALE, NEW YORK, ASSIGNOR TO AMBURSEN CONSTRUCTION COMPANY, INC., OF NEW YORK, N. Y., A CORPORATION OF NEW YORK

DAM

Application filed April 30, 1930. Serial No. 448,505.

This invention relates to a novel and improved form of dam, and the novel features will be best understood from the following description and the annexed drawings, in which.

Fig. 1 is a vertical sectional view through the upstream water bearing deck of a dam, parts being omitted and other parts shown in elevation for the sake of clearness.

10 Fig. 2 is a section on the line 2—2 of Fig. 1.

Figs. 3 and 4 are sections taken on the lines 3—3 and 4—4 respectively, of Fig. 1, the planes of these figures being parallel to that of Fig. 6.

15 Fig. 5 is a section on the line 5—5 of Fig. 1.

Fig. 6 is a transverse section through the upstream water bearing deck and the haunches of the buttresses.

20 Figs. 7 and 8 are diagrammatic vertical sections of dams of the general type shown in this application.

Referring first to Figs. 6, 7 and 8, Fig. 7 shows a dam of the hollow or buttress type, in which there is an upstream water bearing 25 deck 1 supported by a plurality of buttresses 2, these buttresses extending upstream and downstream. While I shall refer to the dam and its parts in relation to a stream across which it is normally built, nevertheless it is

30 to be understood that by the use of that term I do not intend to limit myself to a structure built only to control the flow of a stream. Extending between the buttresses 2 are slabs 3 which are supported on bearing surfaces 4, 35 it being understood that each slab 3 extends between two adjacent buttresses.

In designing a dam of this type according to present practice, it is assumed that the deck is tied to the buttresses intimately 40 enough so that the entire vertical weight of the deck will be transmitted to the buttresses. It is desirable that the weight should be so transmitted because, if it is, it tends to exert a righting effect on the dam as a whole.

45 However, this assumption which is so generally used is actually fallacious, because when constructed, the weight of the deck is not so transmitted to the buttresses.

50 In Fig. 7, there is shown a force diagram in which the line A represents the weight of

the deck and this weight may be resolved into its components B and C, the line B representing the pressure normal to the upstream edges of the buttresses, and the line C representing the tendency of the deck to slide 55 lengthwise of these edges. After the dam has been in service for some time, the deck is very apt, under present conditions, to slide along the edges of the buttresses under the influence of the component C. It has been 60 the practice to provide joints between the deck and the buttresses, but up to the present time such joints have not been designed to resist the force or forces represented by the component C of Fig. 7.

65 In Fig. 8, the line B represents the same force as does the line B in Fig. 7, and the horizontal component D of this force exerts an overturning moment on the buttresses.

Furthermore, according to present practice, the deck may have an upward movement 70 under conditions where there is a rising temperature. This force tends to cause high localization of tensile stresses either on the bearing surfaces of the buttresses or on the 75 upstream face of the dam, resulting in cracking of the buttresses. Such cracks are quite common in this type of dam.

With the above discussion in mind, this 80 invention relates to means for transmitting the entire weight of the deck to the buttresses, so that it may become effective in the manner in which it is now assumed to be effective and, at the same time, for preventing 85 the formation of the aforesaid cracks in the buttresses.

For the purpose of illustration, I shall assume that the upstream deck is formed partly by portions 5 of the buttresses, these portions extending lengthwise of the buttresses. The slabs 3 rest on the bearing surfaces 4 which extend laterally of the buttresses and outwardly from the downstream edges of the sides of the portions 5.

90 Each slab and buttress have contacting surfaces, in one of which is provided longitudinally extending grooves, and in the other of which is provided corresponding tongues or projections disposed in said grooves. In 95 this illustration, there are provided grooves 100

6 in the offset sides of the portions 5, and these grooves are made substantially continuous from top to bottom of the deck. There may be a break in the continuity of these 5 grooves, which is desirable for designing purposes, as will be discussed more fully later on, but the arrangement is such that the slabs may act together for substantially their entire height. These grooves are preferably parallel to the bearing surfaces 4 and to each other.

Extending transversely of the slabs are grooves 7 which are here shown as connecting the longitudinally extending grooves 6, and 15 in these transverse grooves are disposed transverse projections or tongues 8, (Fig. 2), on the slabs. Preferably, each groove 7 has on the upper side thereof a packing 9 of resilient material disposed between the upper 20 side of the projection 8 and the adjacent upper side of the groove. This resilient material is of course of a suitable nature to resist the passage of water, and is designed to take up any vertical movement which may 25 occur, due to upward movement of the deck caused by a rising temperature. The walls of the transverse grooves and the projections disposed in the grooves form interlocking elements which prevent downward sliding 30 of the deck and thus transmit the entire weight of the deck to the buttresses. When for any reason it is desirable to break up the continuity of the longitudinal grooves, such as shown by the offset relation between the 35 grooves 6 and the grooves 6' in Fig. 1, it is desirable to insert resilient material as at 10, Figs. 1 and 5, at the upper ends of the lower grooves. This resilient material will then 40 contact with the projections or tongues on the slabs, which are received in the grooves 6'.

While I refer to two longitudinally extending grooves, of course, this number may be varied, as found desirable. For example, 45 in the upper part of the deck shown in Fig. 1, I may find it desirable to use only one groove 6'', extending transversely of which are short grooves 7''. Here too, resilient material 11 should be deposited at the upper 50 end of the upstream groove 6, this material, of course, contacting with the upper end of the projection in the groove 6.

I claim:—

1. In a dam, a plurality of buttresses extending up- and down-stream, an inclined water bearing deck comprising slabs extending between adjacent buttresses and bearing thereon, each slab having a surface contacting with a surface on a buttress, one of said 55 surfaces having a substantially continuous groove extending generally parallel to the bearing of the slab on the buttress, and the other of said surfaces having a substantially continuous projection received in said groove, and interlocking elements on said surfaces

cooperating to prevent sliding of said projection in said groove.

2. In a dam, a plurality of buttresses extending up- and down-stream, an inclined water bearing deck comprising slabs extending between adjacent buttresses and bearing thereon, each slab having a surface contacting with a surface on a buttress, one of said surfaces having a substantially continuous groove extending generally parallel to the bearing of the slab on the buttress, and other grooves extending transversely to said first-mentioned groove, and the other of said surfaces having a substantially continuous projection received in said first-mentioned groove and transversely extending projections received in said transverse grooves.

3. In a dam, a plurality of buttresses extending up- and down-stream, an inclined water bearing deck comprising slabs extending between adjacent buttresses and bearing thereon, each slab having a surface contacting with a surface on a buttress, one of said surfaces having a substantially continuous groove extending generally parallel to the bearing of the slab on the buttress, other grooves extending transversely to said first-mentioned groove and the other of said surfaces having a substantially continuous projection received in said first-mentioned groove and transversely extending projections received in said transverse grooves, and resilient material disposed between sides of said transverse projections and the adjacent sides of the transverse grooves in which they 100 are received.

4. In a dam, a plurality of buttresses extending up- and down-stream, an inclined water bearing deck comprising slabs extending between adjacent buttresses and bearing thereon, each slab having a surface contacting with a surface on a buttress, one of said surfaces having a substantially continuous groove extending generally parallel to the bearing of the slab on the buttress, other grooves extending transversely to said first-mentioned groove and the other of said surfaces having a substantially continuous projection received in said first-mentioned groove and transversely extending projections received in said transverse grooves, and resilient material disposed between the upper side of each transverse projection and the adjacent side of the transverse groove.

5. In a dam, a plurality of buttresses extending up- and down-stream, each buttress having at its upstream edge a portion extending lengthwise of the buttress, a bearing surface extending laterally of the buttress and disposed at the down-stream edge of one side of said portion, a slab resting on said bearing surface and having a projection disposed in a groove in said side, said projection and groove extending generally parallel to said bearing surface and being substantial- 100

ly continuous approximately from top to bottom of the buttress, and interlocking elements on said surfaces cooperating to prevent sliding of said projection in said groove.

- 5 6. In a dam, a plurality of buttresses extending up- and down-stream, each buttress having at its upstream edge a portion extending lengthwise of the buttress, a bearing surface extending laterally of the buttress and
10 disposed at the down-stream edge of one side of said portion, a slab resting on said bearing surface and having a projection disposed in a groove in said side, said projection and groove extending generally parallel to said
15 bearing surface and being substantially continuous approximately from top to bottom of the buttress, and projections on the slab extending transversely of the first mentioned projection and disposed in grooves in said
20 side.

7. In a dam, a plurality of buttresses extending up- and down-stream, each buttress having at its upstream edge a portion extending lengthwise of the buttress, a bearing surface extending laterally of the buttress and disposed at the down-stream edge of one side of said portion, a slab resting on said bearing surface and having a projection disposed in a groove in said side, said projection and groove extending generally parallel to said bearing surface and being substantially continuous approximately from top to bottom of the buttress, projections on the slab extending transversely of the first-mentioned
35 projection and disposed in grooves in said side, and resilient material disposed between the upper side of each transverse projection and the adjacent side of the groove in which it is received.

- 40 8. In a dam, a plurality of buttresses extending up- and down-stream, an inclined water bearing deck comprising slabs extending between adjacent buttresses and bearing thereon, each slab having a surface contacting with a surface on a buttress, one of said surfaces having projections transversely to the deck and disposed in grooves in the other of said surfaces.

- 45 9. In a dam, a plurality of buttresses extending up- and down-stream, an inclined water bearing deck comprising slabs extending between adjacent buttresses and bearing thereon, each slab having a surface contacting with a surface on a buttress, one of said surfaces having projections transversely to the deck and disposed in grooves in the other of said surfaces, and resilient material disposed between the upper side of each transverse projection and the adjacent side of the
55 groove in which it is received.

EDGAR H. BURROUGHS.
